UNITED STATES PATENT OFFICE.

MYRON H. CLARK, OF MILFORD, CONNECTICUT, ASSIGNOR TO THE GOODYEAR'S
METALLIC RUBBER SHOE CO., A CORPORATION OF CONNECTICUT.

DESIGN FOR A RUBBER BOOT.

48,627.

Specification for Design.

Patented Feb. 29, 1916.

Application filed October 31, 1914. Serial No. 869,702. Term of patent 14 years.

To all whom it may concern:

Be it known that I, MYRON H. CLARK, a citizen of the United States, residing in Milford, county of New Haven, State of Connecticut, have invented a new, original, and ornamental Design for Rubber Boots, of which the following is a specification, reference being had to the accompanying drawing, forming a part thereof.

The figure of the drawing is an elevation of a boot showing my new design.

I claim:

The ornamental design for a rubber boot as shown.

MYRON H. CLARK.

Witnesses:

WARREN D. ABEL,

CHARLES S. MYERS.
